UNITED STATES PATENT OFFICE.

CHRISTIAN A. SCHMIDT, OF HOBOKEN, NEW JERSEY.

DESIGN FOR CHENILLE.

SPECIFICATION forming part of Design No. 14,954, dated April 8, 1884.

Application filed January 17, 1884. Term of patent 14 years.

To all whom it may concern:

Be it known that I, CHRISTIAN A. SCHMIDT, a citizen of Russia, residing at Hoboken, in the county of Hudson and State of New Jersey, have invented and produced a new and original Design for Chenille, of which the following is a specification.

Reference is to be had to the accompanying drawing, forming a part of this specification, in which several samples of my newly-designed chenille are shown.

This invention relates to a new and handsome design for that class of chenille in which the diameter varies, the said chenille being known as "shaped chenille."

My newly-designed chenille consists of shaped chenille A, around which one or more cords or bands, a, are wound spirally.

The variations in the diameter of the chenille can be made according to any desired pattern, and the greatest and least diameter of the chenille can be changed as may be desired.

The shaped sections of the chenille can have greater or less length, as may be desired.

I claim—

The design herein described for chenille, consisting of lengths or sections of varying diameters, and having peripheral lines of spiral convolutions of a different background from the surface.

CHRISTIAN A. SCHMIDT.
